ABSTRACT

This invention relates to an improved method for the preparation of three components of the boll weevil pheromone — Z and E-3,3-dimethylcyclohexylideneacetaldehyde and Z-3,3-dimethylcyclohexylidenethanol. A Wittig reagent prepared from diethyl cyanomethylphosphonate and base in a suitable solvent is used to convert 3,3-dimethylcyclohexanone to Z and E-3,3-dimethylcyclohexylideneacetonitrile. The latter two compounds are converted to the corresponding aldehydes by reduction followed by in situ hydrolysis. These aldehydes represent two of the active components of the boll weevil sex pheromone. The stereochemistry of the nitrile intermediate resulting from the Wittig reaction can be controlled to a degree by altering solvent and base. Reduction and hydrolysis provide aldehydes stereochemically rich in a given isomer. Subsequent reduction of the aldehyde mixture provides a mixture of Z and E-3,3-dimethylcyclohexylidenethanols with the same isomer distribution as in the aldehyde precursor. Alternatively, isomers can be separated at the nitrile, aldehyde, or alcohol stage.

2 Claims, No Drawings

3,3-DIMETHYLCYCLOHEXYLIDENEACETONITRILES

Insect sex attractants (pheromones) are of considerable interest and economic importance in that they offer a nontoxic ecologically acceptable method of surveying and controlling insect populations. The components of the pheromone emitted by the male boll weevil (*Anthonomus grandis* Boheman) are known to be terpenoids I, II, III and IV. (Tumlinson, et al., *Science* 166, 1012, 1969)

I

II

III

IV

Table 1, taken from Tumlinson (supra), indicates the effectiveness of various combination of I through IV in attracting female boll weevils as compared to the naturally occurring pheromone. Response of female boll weevils in laboratory bioassay to optimum concentrations of compounds I, II, III and IV. The T/S equals net response to test sample divided by net response to a standard. The sample in each case consisted of the compound or the indicated mixture of compounds in

0.2 ml. of dichloromethane. The standards used were live male boll weevils or steam distillates that were equivalent in attractancy to live males.

5

Sample	Respective amounts (μ g)	Average T/S
I	0.09	0.11
II	0.07	0.06
III	0.12	0.00
IV	0.12	0.11
I, II	0.09, 0.07	0.15
I, III	0.09, 0.12	0.06
I, IV	0.09, 0.12	0.12
II, III	0.07, 0.12	0.24
II, IV	0.07, 0.12	0.12
III, IV	0.12, 0.12	0.16
I, II, III	0.09, 0.07, 0.12	1.00
I, II, IV	0.09, 0.07, 0.12	0.84
I, III, IV	0.09, 0.12, 0.12	0.07
II, III, IV	0.07, 0.12, 0.12	0.18
I, II, III, IV	0.09, 0.07, 0.12, 0.12	1.26

Since III and IV are combined in equimolar quantities in the pheromone composition, it is evident that the

25 ZE isomers do not need to be separated.

The object of this invention is to provide an improved method for the preparation of Z and E-3,3-dimethylcyclohexylideneacetaldehyde (III and IV). Mixtures of Z and E-3,3-dimethylcyclohexylideneethanol, which are rich in the Z isomer (II), are easily prepared in the context of the process of the present invention. Preparation of the pure Z-3,3-dimethylcyclohexylideneethanol, (II), is somewhat less efficient than preparation of the aldehyde mixture because of the necessity to separate isomers at some stage of the process.

30 These compounds have previously been prepared through laborious multistep processes by Tumlinson et al., *J. Org. Chem.*, 36, 2616 (1971). The present invention relates to a novel process for preparing terpenoids II, III, and IV. This process (Scheme I) is characterized by simplicity, high yield, and some degree of stereochemical control.

The first step of this process involves the reaction between 3,3-dimethylcyclohexanone and a Wittig reagent, prepared from a dialkyl cyanomethylphosphonate, in a solvent containing a base. Non-polar and polar solvents are used. Suitable non-polar solvents are benzene-pentane mixtures and suitable polar solvents are alcohols, such as ethanol and tertiary-butyl alcohol, dimethylformamide (DMF) and dimethylsulfoxide (DMSO). Among operative bases are methyl lithium, sodium hydride, alkali metal alkoxides and tetraalkyl ammonium hydroxides. The preferred base/solvent system is sodium hydride in a polar solvent such as dimethylsulfoxide or dimethylformamide. This combination of base and solvent is preferred since it provides an excess of the Z-3,3-dimethylcyclohexylideneacetonitrile which, in turn, is required for the preparation, by subsequent steps of mixtures of alcohols rich in Z 3,3-dimethylcyclohexylidenethanol, II.

Table 2 shows the E and Z isomer distribution of 3,3-dimethylcyclohexylideneacetonitrile as a function of base and solvent.

TABLE 2

Z-isomer	E-isomer	Base	Solvent
28	72	CH ₃ Li	C ₆ H ₆
50	50	NaH	9:1 C ₆ H ₆ -pentane
45	55	NaOC ₂ H ₅	CH ₃ CH ₂ OH
50	50	NaOC(CH ₃) ₃	(CH ₃) ₂ COH
65	35	NaH	DMF or DMSO
28	72	(CH ₃ CH ₂ CH ₂ CH ₂) ₄ NOH ⁺	1:1 C ₆ H ₆ -CH ₃ OH

The second step involves the reduction of the E and Z nitriles to E and Z imines followed by hydrolysis to the corresponding aldehydes. Alkyl substituted metal hydrides are the preferred reducing agents and diisobutylaluminum hydride is the most preferred. The resulting Z and E-3,3-dimethylcyclohexylideneacetaldehydes are present in the same ratio as that of the E and Z nitrile precursors. Standard reducing agents convert the aldehyde mixture to E and Z alcohols. Sodium borohydride performs this conversion quantitatively.

When the Wittig reaction is conducted in dimethylformamide, using sodium hydride as the base, the 3,3-dimethylcyclohexylideneacetonitriles are present in a Z/E ratio of 65/35. This mixture of nitriles is converted to Z-3,3-dimethylcyclohexylidenethanol containing the E isomer by the steps indicated above and the Z isomer is purified by standard separation techniques such as fractional distillation, vapor phase chromatography, or column chromatography. Alternatively, the Z and E-3,3-dimethylcyclohexylideneacetonitrile isomers are separated prior to the nitrile reduction, hydrolysis, and aldehyde reduction steps. It is not necessary to purify each component since it is the mixture of I, II, III, and IV which forms the effective pheromone. This invention therefore presents an improved method for the preparation of three of the active components of the boll weevil pheromone.

The key intermediate in this process, Z-3,3-dimethylcyclohexylideneacetonitrile is an antagonist for prostaglandin E₂ and bradykinin, in contrast to cyclohexylideneacetonitrile (Brande and Wheeler, *J. Chem. Soc.*, 321, 1955) which is an antagonist for prostaglandin E₂ but not for bradykinin.

The bradykinin-antagonist properties of the compounds of the present invention are evidenced by results of the following test. Two Charles River female rats weighing 240-280 grams are treated on each of two successive days with diethylstilbestrol in order to induce a state of estrus. On the third day the animals are sacrificed and the uteri are removed. A 10 mm. section is taken from one of the uteri and suspended in a tissue bath containing 1.9 ml. of Tyrode's solution, prepared as described by Barnes and Eltherington, *Drug Dosage in Laboratory Animals*, p. 261, University of California Press, Berkeley, California (1964). The tissue bath is surrounded by a water jacket maintained at a constant temperature of 30°C. The concentration of bradykinin in the tissue bath is then gradually increased by successive additions of bradykinin dissolved in Tyrode's solution. The bradykinin solution concentration is defined as the pD, which is the log of the reciprocal of the concentration expressed in mg./ml. At each of the selected bradykinin concentrations, contraction of the uterus is measured in mm. by means of an E & M Physiograph used together with an Isotonic Myograph Transducer and Detecting Head. After completion of those measurements the tissue is rinsed nine times over a period of 9 minutes with fresh Tyrode's solution. The last rinse is kept in the bath and 100 mcg. of the test compound dissolved or suspended in 0.1 ml. of Tyrode's solution is injected into the bath, which consists of 1.9 ml. of Tyrode's solution. The contractions at each concentration are measured as before and are compared with the control values, i.e., those obtained in the absence of the test compound. The identical procedure is then carried out with the 10 mm. section of the uterus taken from the second animal. A compound is considered active either if it inhibits by at least 10 percent the maximum bradykinin-induced contraction or if it causes an increase of at least 0.3 pD unit in bradykinin concentration required to effect 50 percent of the maximum contraction.

The PGE₂ antagonist properties of the compounds of the present invention are evidenced by results of the following test. The test procedure is substantially that described by J. H. Sanner, *Arch. int. Pharmacodyn.*, 180 (1), 46 (1969). Female albino guinea pigs weighing 200-500 g. are sacrificed by cervical dislocation and the ileum is quickly removed and placed in modified Tyrode's solution containing one-half the usual amount of magnesium ions. Segments of ileum, about 2 cm. long, are cut and mounted in a 2 or 4 ml. tissue bath containing the modified Tyrode solution. The solution is maintained at 37° and bubbled with a gaseous mixture of 95 percent oxygen and 5 percent carbon dioxide. Contractions are detected tonically. Approximately equal submaximal contractions are obtained at 4.0 minute intervals. A solution or suspension of the test compound in the bathing solution is then substituted for the original modified Tyrode's solution. The test suspension is kept in constant contact with the tissue for the remainder of the experiment except for brief periods to drain the bath in preparation for rinsing with fresh test suspension. Three more contractions are elicited to each agonist in the presence of the test compound without interrupting the time sequence. The last 2 sets of treated responses are compared with the 2 sets of control responses. The first set of treated responses is not used for comparisons, being used only to main-

tain the timed sequence of injections during the period allowed for the tissue to become equilibrated with the antagonist. The compound is rated active if the mean of contractions produced by any agonist is reduced 75 percent or more by the test compound.

EXAMPLE 1

In an inert atmosphere, 1.89 parts of diethyl cyanomethylphosphonate in 5 parts by volume of dimethylformamide are added to a cold ($\sim 15^\circ$) suspension of 0.25 part of sodium hydride in 5 parts by volume of dimethylformamide. This mixture is brought to room temperature and a solution of 1.26 parts of 3,3-dimethylcyclohexanone in 10 parts by volume of dimethylformamide is added to the above base solution. After 1 hour, 50 parts by volume of water are added and the product is separated from the reaction mixture by extraction with pentane. The product is purified by fractional distillation and the isomers are separated by vapor phase chromatography on a 12 foot column packed with 10 percent tetracyanoethylated pentaerythritol on Aeropak 30, 80/100 mesh at 120° . The Z-3,3-dimethylcyclohexylideneacetonitrile has an nmr spectrum which is characterized by a 6 proton geminal methyl proton absorption at 0.99δ and a single vinyl proton absorption at 5.12δ . The corresponding E-3,3-dimethylcyclohexylideneacetonitrile isomer absorptions are, respectively, 0.935δ and 5.01δ . The formulas are:

EXAMPLE 2

To a solution of 1.35 parts of a mixture of E and Z-3,3-dimethylcyclohexylideneacetonitrile in 20 parts by volume of benzene is added 1.42 parts of 40 diisobutylaluminum hydride. After 4 hours, 120 parts by volume of saturated ammonium chloride solution is added and the product is isolated by ether extraction. The ether extracts are washed successively with 5 percent hydrochloric acid, saturated sodium bicarbonate, 45 10 percent sodium chloride solution. The ether extracts are then dried over anhydrous magnesium sulfate and filtered. The ether is removed by evaporation at reduced pressure to provide E and Z-3,3-dimethylcyclohexylideneacetaldehyde. The formulas are:

EXAMPLE 3

10 1.5 parts of 65/35 mixture of Z/E stereoisomers of 3,3-dimethylcyclohexylideneacetaldehyde is added to 30 parts by volume of absolute ethanol containing 0.2 parts of sodium borohydride. After 1 hour, the reaction mixture is poured into 150 parts by volume of water and the aqueous layer is then saturated with sodium chloride. The product is isolated by extraction with pentane. The pentane extracts are washed with 10 percent sodium chloride and dried over magnesium sulfate. Removal of the solvent by evaporation at reduced 15 pressure provides a 65/35 mixture of the Z/E stereoisomers of 3,3-dimethylcyclohexylideneethanol. The formulas are:

EXAMPLE 4

25 Z-3,3-dimethylcyclohexylideneethanol is prepared from Z-3,3-dimethylcyclohexylideneacetonitrile exactly as the Z and E mixture of nitriles is converted to the mixture of Z and E alcohols in Examples 2 and 3. The formula is:

What is claimed is:

1. The mixture of Z and E-3,3-dimethylcyclohexylideneacetonitrile containing 28 to 65 percent Z-3,3-dimethylcyclohexylideneacetonitrile.
2. Z-3,3-dimethylcyclohexylideneacetonitrile.
